NEEDLE BAR DYNAMIC BALANCER

Waldemar A. Ayres, Lakewood, Ohio, assignor to White Sewing Machine Corporation, Lakewood, Ohio, a corporation of Delaware

Application July 14, 1954, Serial No. 443,259

6 Claims. (Cl. 112—221)

This invention relates to a sewing machine and more particularly to an improved and novel arrangement in a sewing machine for dynamically balancing the needle bar and the actuating mechanism therefor.

One of the limitations to the operating speeds of a sewing machine is the objectionable vibrations set up by the moving parts as, for instance, a part such as the reciprocating needle bar, operating at high speeds. The magnitude of the vibrations limits the operating speeds of the sewing machine and necessitates the use of slower operating speeds to maintain the vibrations at a minimum and to lessen the operating noises present in the machine.

The main general object of the invention is to provide an improved dynamically balanced needle bar mechanism in a sewing machine.

Another object is to provide in a sewing machine an improved and novel arrangement for dynamically balancing the needle bar and operating mechanism therefor which substantially eliminates vibrations in the sewing machine head occasioned by the reciprocation of the needle bar, even though the machine is operating at high speeds and thus produces a quieter and more efficient sewing machine.

A further object is to provide in a sewing machine an improved and novel arrangement for dynamically balancing the needle bar and wherein a reciprocating mass moves parallel to the reciprocating needle bar in oppositely phased relationship thereto while said needle bar and said mass are actuated by rotatable elements coaxial with the horizontal main shaft in the horizontal arm of the sewing machine head.

An additional object is to provide in a sewing machine improved and novel means for dynamically balancing the needle bar, as referred to in the last named object, and with which a rotatable thread take-up coaxial with the main shaft may be combined and driven by the rotatable elements that actuate the needle bar and the balancing means.

Another object of the invention is to provide in a sewing machine an arrangement such as defined in the previous objects and which is simple compact and does not substantially increase the size of the sewing machine head.

Further and additional objects and advantages not hereinbefore referred to will become apparent hereinafter during the detailed description of embodiments of the invention which are to follow and which embodiments are illustrated in the accompanying drawings forming part of this specification and wherein,

Fig. 1 is a fragmentary view of the horizontal arm of a sewing machine head, said horizontal arm being shown partly in elevation while the outer or needle bar carrying or face end of the arm is shown in section to illustrate one form of the needle bar actuating mechanism and the dynamic balancing means embodying the present invention.

Fig. 2 is a sectional view taken substantially on line 2—2 of Fig. 1 looking in the direction of the arrows.

2

Fig. 3 is a sectional view taken substantially on line 3—3 of Fig. 1 looking in the direction of the arrows.

Fig. 4 is a view similar to Fig. 1 but illustrates another embodiment of the invention, and

Figs. 5 and 6 are sectional views taken, respectively, substantially on lines 5—5 and 6—6 of Fig. 4, looking in the direction of the arrows.

Although only a portion of the horizontal arm 10 is illustrated it will be understood that the sewing machine head includes the usual vertical portion or standard at the opposite end of the horizontal arm from the face end shown in Fig. 1. It will also be understood that the vertical portion or standard of the head extends upwardly from the sewing machine bed and that said bed mounts and supports suitable hook and feed mechanisms and the shafts for operating the same and which shafts are operatively interconnected to the main shaft 11 that is rotatably mounted in suitable bearings in the horizontal arm 10, one of such bearings being indicated at 12.

Any suitable power means can be employed for operating the sewing machine. The free end of the horizontal arm 10 is generally indicated as the face of the sewing machine, such face being designated herein as 13. The face 13 slidably supports a vertically reciprocating needle bar 14 which carries at its lower end a needle and is so located as to cooperate with the hook and feed mechanisms previously referred to to effect a sewing operation all as will be well understood in the art. The face end 13 of the arm also will mount any well known form of presser foot mechanism.

The main shaft 11 to the left of the bearing 12 as viewed in Fig. 1 extends into a chamber 15 formed in the end of the horizontal arm 10. Within the chamber 15 the shaft 11 has fixed thereto or integral therewith in coaxial relationship a disk 16. The disk 16 is provided on its face that is remote to the bearing 12 with a pin 17 which may be integral with the disk or rigidly secured thereto and which is eccentric to the axis of the shaft 11 but is parallel to said shaft and will be hereinafter referred to as an eccentric pin. The pin 17 is rigidly connected to the right hand face, as viewed in Fig. 1, of a disk 18 of the same size and mass as the disk 16 and located coaxially with said disk 16 and shaft 11. The disk 18 on its opposite face mounts an eccentric pin 19 similar to the pin 17 but 180° out of phase therewith. The pin 19 is rigidly connected to the end of a stub shaft 20 coaxial with the shaft 11 but of larger diameter than the shaft 11 and which is rotatably supported in a bearing 21 and extends outwardly of the face 13 of the horizontal arm and into a recess 22 formed in said face.

A rotary thread take-up mechanism is connected to the outer end of the stub shaft 20 and comprises a disk 23 concentrically and rigidly connected to the stub shaft 20 and located in the recess 22 and a second disk 24 coaxial with the first disk but spaced outwardly therefrom and rigidly interconnected therewith by an eccentric pin 25.

From the foregoing description it will be seen that rotation of the main shaft 11 simultaneously effects rotation of the disks 16 and 18, the stub shaft 20 and the disks 23 and 24 of the rotary thread take-up mechanism, all of said parts being arranged in coaxial relationship.

The needle bar 14 previously referred to reciprocates in a vertical bore formed in the horizontal arm 10 below the chamber 15 and projects into said chamber. The upper end of the needle bar 14 within the chamber 15 is provided with a Scotch yoke 26 that is rigidly connected to the upper end of the needle bar and which has its elongated opening extending in a horizontal direction.

The eccentric pin 19 passes through a shoe 27 that is slidably mounted in the elongated opening of the Scotch

yoke 26 from which it will be seen that rotation of the disk 18 by the shaft 11 causes reciprocating movement of the needle bar 14.

The horizontal arm 10 to the right of the needle bar 14 as viewed in Fig. 1 and in horizontal alignment therewith and parallel thereto, contains a vertical bore 28 extending from the underside of the arm 10 upwardly to the chamber 15. In addition, the arm 10 above the chamber 15 has a second vertical bore 29 that is in vertical alignment with the bore 28 and which communicates with the chamber 15.

A counterbalancing mass in the form of a rod 30 has its opposite ends slidably mounted in the bores 28 and 29 and extends through the chamber 15. The rod 30 intermediate its ends and within the chamber 15 is provided with a Scotch yoke 31, the elongated opening in which extends horizontally.

The eccentric pin 17 extends through a shoe 32 slidably mounted in the elongated opening of the Scotch yoke 31. Hence it will be seen that the rotation of the shaft 11 and the disk 16 imparts vertical reciprocating movement to the rod 30. As already stated, the eccentric pins 17 and 19 are 180° out of phase and hence rotation of the main shaft 11 will effect oppositely phased reciprocation of the needle bar 14 and the rod 30.

The mass of the rod 30 and its Scotch yoke 31 equals the mass of the needle bar 14, its Scotch yoke 26 and the needle mounted in the lower end of the needle bar. The disks 16 and 18 are of the same mass and are concentrically rotated while the eccentric pins 17 and 19 are of the same mass. Consequently the rotation of the shaft 11, disks 16 and 18 and the pins 17 and 19 therewith effect dynamically balanced oppositely phased reciprocation of the needle bar 14 and rod 30. Thus the operation of the mechanism and the oppositely phased reciprocation of the dynamically balanced needle bar and rod 30 cause opposing vibrations to cancel out and the operating speeds can be materially increased because of this fact.

The arrangement for dynamically balancing the reciprocating needle bar is compact inasmuch as the mechanism for reciprocating the needle bar and for reciprocating the balancing rod 30 is formed of elements arranged coaxially with the main shaft 11 and all contained in the chamber 15. Also the arrangement advantageously enables the rotatable thread take-up mechanism comprising the disks 23 and 24 and the pin 25 to be arranged coaxially with the main shaft 11 and to be actuated by the disk 18 and stub shaft 20 and located on the outside of the face 13 of the horizontal arm 10.

In Figs. 4 to 6 inclusive, a different form of construction embodying the invention is illustrated. This modified form may be considered as the preferred embodiment.

Referring to Fig. 4, the outer or free end of the horizontal arm of the sewing machine head is indicated at 33. The face end 34 of the arm 33 extends downwardly and is hollow and has secured therein a bearing mass 35 the purpose of which will later become apparent.

The main shaft in the arm 33 is indicated at 36 and said shaft is operatively connected to the sewing mechanism below the bed plate as described in connection with the main shaft 11. The shaft 36 is rotatably supported in the arm 33 by a suitable number of bearings, one of which is shown in Fig. 4, and comprises a bearing bracket 37 secured to, or formed integral with, the interior of the arm 33 and provided with an opening mounting a bearing sleeve or bushing 38.

A disk 39 has a hub 40 fitting the end of the shaft 36 and rotatably interfitting the bearing bushing 38 and secured to the shaft 36 as by the pin 41 to rotate with said shaft. The disk 39 may be readily assembled with the shaft 36 and has secured to, or integral with, its outer face an eccentric pin 42.

The pin 42 is secured to, or integral with, the adjacent face of a disk 43 and is located eccentrically to the axis

of the disk 43 which, in turn, is coaxial with the disk 39 and shaft 36. The disk 43 has secured to, or integral with, its outer face an eccentric pin 44 that is 180° out of phase with the eccentric pin 42.

The eccentric pin 44 is eccentrically secured to, or integral with, the adjacent face of a disk 45 that is coaxial with the disks 43 and 39 and shaft 36. The disk 45 on its outer face has a central boss 46. The disks 45, 43 and 39 and pins 44 and 42 constitute a double crank arm which may be machined as an integral member or which can be assembled from separately made parts and which rotates with and forms an extension of the shaft 36.

The end face 34 of the arm 33 is provided with an opening 47 in which is located the disk 48 of a rotary thread take-up mechanism. This take-up mechanism also includes a second disk 49 located outwardly of, and spaced from, the disk 48 and coaxial therewith. The disks 48 and 49 are interconnected by an eccentric pin 50. The thread take-up mechanism is secured coaxially to the boss 46 of the disk 45 by a screw 51 carried by the disk 48 and screwing into the disk 45 with the head of the screw 51 accessible through an opening 52 in the disk 49.

The bearing mass 35 is provided with a vertical bore the upper end of which is outwardly tapered or enlarged as indicated at 53 in Figs. 4 and 5. This vertical bore aligns with an opening in the underside of the face 34 and slidably mounts a reciprocating needle bar 54 which projects through said opening and is adapted to mount in its lower end a needle, as will be well understood.

The upper end of the needle bar 54 is slotted to provide a pair of parallel ears 55 provided with aligned openings having bearing bushings therein mounting a pivot pin 56. The lower end of a pitman arm 57 extends between the ears 55 and is pivoted on the pin 56. The upper end of the pitman arm 57 has a semicylindrical yoke 58 embracing the lower half of the pin 44 while a semicylindrical clamping collar 59 is secured to the yoke 58 and embraces the upper half of the pin 44, a suitable bearing bushing 60 surrounding the pin 44 within the yoke and collar. It will be understood that rotation of shaft 36 reciprocates needle bar 54 through pin 44 and pitman arm 57, with the movement of the latter accommodated in the enlarged upper end 53 of the needle bar bore.

The mass 35 is provided with a larger vertical bore 61, the upper end of which is outwardly tapered or enlarged as indicated at 62; see Figs. 4 and 6. A counterweight rod 63 slidably reciprocates in the bore 61 and has a reduced upper end 64 which is slotted to provide a pair of parallel ears 65 having aligned openings provided with bearing bushings and mounting a pivot pin 66.

The lower end of a pitman arm 67 extends between the ears 65 and is connected to the pin 66. The upper end of the pitman arm 67 has a half yoke 68 embracing the lower half of the pin 42. A clamping head or collar 69 is secured to the half yoke 68 and embraces the upper half of the pin 42, a bearing bushing or sleeve 70 surrounding the pin 42 within the half yoke 68 and collar 69. It will be seen that rotation of shaft 36 effects reciprocation of the counterweight rod 63 through the pin 42 and pitman arm 67, the enlarged end 62 accommodating the movement of the pitman arm. A vent opening 61a may be provided in the underside of the end 34 beneath the bore 61.

It will be understood that the needle bar 54 and rod 63 during rotation of shaft 36 reciprocate simultaneously but in opposite phase. The masses of the rod 63 and the needle bar 54, as well as of the disks 39, 43, 45, 48 and 49 are so inter-related that opposing forces are dynamically balanced or counterpoised wherefore vibration is reduced to a minimum thus enabling higher operating speeds to be utilized in the sewing machine.

Although several embodiments of the invention have been described and shown for illustrative purposes, it will be understood the invention is susceptible of various

modifications and adaptations within the scope of the appended claims.

Having thus described my invention, I claim:

1. In the horizontal arm of a sewing machine head, a horizontal rotatable main shaft terminating short of the free end of said arm, a first vertical bore extending to the underside of the free end of said arm, a reciprocable needle bar mounted in said first bore, a second vertical bore spaced from said first bore and parallel therewith, a counterbalance correlated in mass to said needle bar reciprocable in said second bore, a first disk secured to the end of said main shaft and coaxial therewith, a second disk coaxial with but spaced from said first disk and interconnected therewith by an eccentric pin extending between said disks, a third disk coaxial with said first and second disks and spaced from the latter and interconnected with said second disk by an eccentric pin extending therebetween and 180° out of phase with said first named eccentric pin, a pitman interconnecting said last named eccentric pin and said needle bar, and a second pitman interconnecting said first named eccentric pin and said counterweight, said disks and pins and pitmans being correlated in mass, as are said needle bar and counterweight, to provide counterbalancing opposing forces during rotation of said shaft and reciprocation of said needle bar and said counterweight.

2. In the horizontal arm of a sewing machine head as defined in claim 1 and wherein said first named disk is provided with a hub interfitting the end of the main shaft and secured thereto and rotatable in a bearing provided interiorly of said arm.

3. In the horizontal arm of a sewing machine head as defined in claim 1 and wherein a rotary thread take-up is provided which comprises two axially spaced coaxial disks interconnected by a pin extending therebetween adjacent their circumferences, said rotary thread take-up being secured to said third disk coaxially therewith and having one of the disks of the take-up located in an opening formed in said arm and the other disk thereof together with the pin interconnecting said disks of the take-up located exteriorly of said arm.

4. In the horizontal arm of a sewing machine head, a rotatable horizontal main shaft, a vertically reciprocal needle bar, a vertically reciprocal counterbalance correlated in mass to said needle bar, and operative connections between said shaft and said needle bar and said counterbalance to impart to said needle bar and counterbalance oppositely phased reciprocation from the rotation of said shaft and including identical disks coaxial with said shaft and spaced axially with respect to each other and located beyond the end of the shaft, with said disks interconnected by an eccentric pin and with one of said

disks connected to said shaft and the other of said disks mounting an eccentric pin on the face thereof remote to said first named pin and displaced 180° therefrom, the eccentric pin interconnecting said disks being operatively connected with said counterbalance and the second named eccentric pin carried by said other disk being operatively connected with said needle bar.

5. In the horizontal arm of a sewing machine head as defined in claim 4 and wherein a chamber is formed in the free end of said arm and said horizontal rotatable main shaft terminates in said chamber, a vertical bore extending from said chamber to the under side of said arm, said vertically reciprocal needle bar being mounted in said bore and having its upper end located in said chamber and formed with a Scotch yoke, a vertical bore spaced from said first bore in horizontal parallel alignment therewith and extending from said chamber to the underside of said horizontal arm, a third bore in said horizontal arm in vertical alignment with said second bore and extending upwardly from said chamber, said vertically reciprocal counterbalance being correlated in mass to said needle bar and its Scotch yoke and having rod portions reciprocal in said second and third bores and a Scotch yoke thereon being located in said chamber, said identical disks including a disk in said chamber fixed to and coaxial with said shaft, a second and identical disk in said chamber coaxial with said first disk and said shaft and spaced axially therefrom, an eccentric pin interconnecting said disks and passing through the Scotch yoke of said counterbalance, an eccentric pin carried by said second named disk and 180° out of phase with said first named eccentric pin and passing through the Scotch yoke of said needle bar.

6. In the horizontal arm of a sewing machine head as defined in claim 5 and wherein said horizontal arm is provided at its end with a bearing bore communicating with said chamber and extending to the end of said arm and coaxial with said main shaft, a stub shaft rotatable in said bearing bore and interconnected with said second named disk by the second named eccentric pin carried by the latter, and rotary thread take-up means located exteriorly of the end of the horizontal arm and operatively connected to said stub shaft.
